UNITED STATES PATENT OFFICE.

BURNSIDE E. SAWYER, OF FITCHBURG, MASSACHUSETTS, ASSIGNOR TO DIADEM MANUFACTURING COMPANY, OF FITCHBURG, MASSACHUSETTS, A CORPORATION OF MASSACHUSETTS.

DISPLAY-CARD.

1,113,580.

Specification of Letters Patent. Patented Oct. 13, 1914.

Application filed February 2, 1914. Serial No. 815,862.

To all whom it may concern:

Be it known that I, BURNSIDE E. SAWYER, a citizen of the United States, residing at Fitchburg, in the county of Worcester and

5 State of Massachusetts, have invented a new and useful Display-Card, of which the following is a specification.

This invention relates to a display card particularly adapted for holding and exhibiting celluloid hairpins or other articles of similar formation. Such articles have a highly polished surface and the parts thereof are of substantially uniform cross section throughout. These two characteristics 10 combined make it very difficult to prevent their accidental displacement when mounted in a display card.

It is the object of my present invention to provide an improved form of display card 20 which will effectively retain articles of this class when mounted therein and in which the probability of accidental displacement is very slight.

With this object in view my invention 25 comprises a display card having two parallel series of incisions therein, these incisions being formed and relatively located in such manner as to securely hold hairpins and similar articles inserted therein.

30 The preferred form of my invention is shown in the drawings in which—

Figure 1 is a plan view of a display card having several hairpins mounted therein; Fig. 2 is a view similar to Fig. 1 but showing the reverse side of the card; and Fig. 3 is a transverse sectional view taken along the line 3—3 of Fig. 1.

As shown in the drawing my invention 35 comprises a card A formed of any suitable 40 sheet material and having two parallel series of incisions B and C formed therein. The incisions B are U-shaped, each incision forming a tongue of corresponding outline which is secured to the body of the card along an edge b which is substantially parallel to the axis of the series B. Each incision C is 45 V-shaped and is so located that the point of the V is substantially upon the axis of the series C. Each incision C forms a tongue of 50 corresponding shape secured to the body of the card along the edge c which is substantially at right angles to the axis of the series

C. The incisions in each series are alined transversely and are spaced longitudinally to correspond to the particular articles which 55 are to be mounted upon the card.

One form of hairpin is indicated at D. When mounted upon the card, each leg of the pin extends through one incision of each series, pressing backward the tongues formed 60 by the incisions. The V-shaped incisions C present two oppositely inclined gripping edges which engage any article inserted therein and effectively prevent accidental displacement thereof. At the same time the 65 tongues in the two series press against the rear face of the article and assist in retaining it in the card.

Having thus described my invention, it will be evident that changes and modifications can be made therein by those skilled in the art without departing from the spirit and scope of the invention as set forth in the claims annexed and I do not wish to be limited to the specific details herein dis- 70 closed, but

What I do claim is:—

1. A display card having two parallel series of incisions formed therein, the incisions in one series being U-shaped, and each 80 forming a tongue secured to the body of the card along an edge parallel to the axis of the series, and the incisions of the other series being V-shaped and each forming a tongue secured to the body of the card along 85 an edge transverse to the axis of the series.

2. A display card for hairpins having two series of incisions formed therein, the incisions in the two series being alined transversely and so spaced longitudinally that 90 each leg of each pin may extend through the card at one incision in each series, the incisions in one series being V-shaped with the point of the V on the axis of the series and the edges of the incisions forming oppositely 95 inclined gripping elements effective to prevent accidental displacement of said pins.

In testimony whereof I have hereunto set my hand, in the presence of two subscribing witnesses.

BURNSIDE E. SAWYER.
